(57) **CLAIM**

The ornamental design for a computer, as shown and described.

DESCRIPTION

FIG. 1 is a top, front, left-side perspective view of a computer in accordance with our new design;

FIG. 2 is a front elevational view of the computer shown in FIG. 1;

FIG. 3 is a rear elevational view of the computer shown in FIG. 1;

FIG. 4 is a right-side elevational view of the computer shown in FIG. 1;

FIG. 5 is a left-side elevational view of the computer shown in FIG. 1;

FIG. 6 is a top plan view of the computer shown in FIG. 1; and,

FIG. 7 is a bottom plan view of the computer shown in FIG. 1.

The dash-dash broken lines immediately adjacent the shaded areas represent the bounds of the claimed design. All other dash-dash broken lines depict portions of the computer which form no part of the claimed design. The computer is shown with a dash dot dash broken line illustrating a symbolic break in length. The break lines and the appearance of any portion of the article between the break lines form no part of the claimed design.
